UNITED STATES PATENT OFFICE.

LEO BIRNBAUM, OF NEW YORK, N. Y.

POWDER CONTAINER.

Application filed November 4, 1920, Serial No. 421,645. Renewed April 17, 1924.

To all whom it may concern:

Be it known that I, LEO BIRNBAUM, a citizen of the United States, residing in the borough of Manhattan, of the city of New York, in the State of New York, have invented certain new and useful Improvements 5 in Powder Containers, of which the following is a specification, reference being had to the accompanying drawing, forming a part 10 hereof.

Tooth powder while still preferred by many to tooth paste is packaged in such manner as to make its use uneconomical, tedious and difficult of uniform application 15 to the bristles in the desired quantity. Of course it is recognized that a moistened tooth brush cannot be applied directly to the powder within a container, since this would wet and clog a great portion of the remaining 20 powder and probably result in the application of an excessive quantity to the bristles. On the other hand, when the powder is shaken from a container in the usual manner, it is not only difficult to direct it on to 25 the bristles without an appreciable wastage but the time involved is great and the quantity deposited is not apt to be uniform or approximate to the requirements. The present invention has for its object to provide a 30 container for tooth powder which shall be of such design as to overcome many objections to the use of tooth powder which really affect its popularity, and which shall permit a predetermined quantity of powder 35 to be separated out from the bulk and presented after a simple and quick manipulation to the bristles of the brush for a single cleansing of the teeth. A further object of 40 the invention is to provide a container of the character described which shall itself be simple of construction, inexpensive to manufacture, easy of manipulation and of an attractive form having, aside from its utilitarian purpose, a real advertising value. In 45 accordance with the invention there is provided in a container of suitable outline a sliding partition adjacent the open end, between which and the hinged top there can be entrapped a charge of powder adequate 50 for one cleansing operation and presenting a superficial surface of about equal to that of the average sized tooth brush.

The preferred embodiment of the invention is illustrated in the accompanying drawing, wherein—

Figure 1 is a view in perspective of the

improved container showing the top open and the sliding partition pushed in.

Figure 2 is a view in transverse section 60 through the container shown in Figure 1 with the top closed.

Figure 3 is a fragmentary view in longitudinal section through the top and partition of the container taken on the plane indicated 65 by the line 3—3 of Figure 2.

It will be understood as the description proceeds that the container is not to be limited to the details of manufacture, which, in the preferred embodiment, tend to make for a very cheap construction, nor to the form 70 or dimensions of the container itself. However, it will usually be desirable to make the container of generally rectangular outline so as to receive conveniently at the open end the bristles of a tooth brush which is of generally rectangular outline. The container *a* has hingedly secured thereto at its open end a top *b*, on one edge of which is carried a spring clasp *b'* of such form as to maintain 75 the top releasably in closed position. Adjacent to the open end of the container *a* is mounted a sliding plate *c* preferably passing through a slot *a'* cut in the side wall of the container on the side opposite the hinge *b* for the top *b*. The end walls of the container *a* in line with the slot *a'* may be crimped, as at *a*², to form guide grooves in 80 which is supported slidably the plate *c*. If desired, the plate *c* can be stamped out with ears *c'*, at its opposite edges, which ears are 85 adapted to enter the grooves *a*² and guide and support the plate in its movements. The plate may also have stamped along its rear edge, preferably adjacent the ends thereof, ears *c*², one of which may be turned 90 upwardly and the other turned downwardly 95 to abut against the rear wall of the container *a* when the plate is pushed fully in and abut against the front wall and limit the outward movement of the plate when the latter is 100 pulled out. These ears *c*² also rest against the end walls of the container to limit the lateral movements of the plate. On the outer edge of the plate *c* can be secured in any suitable manner a strip *c*³, which constitutes 105 in effect a double flange extending on opposite sides of the slot *a'*, so as to close the latter completely when the plate is pushed in, and also a convenient finger grip whereby 110 the plate can be manipulated readily whether being drawn out or pushed in. It will be found convenient to have the flanged strip

*c*³ so formed with relation to the clasp *b'* of the top *b* that the clasp will overlie the strip when the slide is pushed in and the cover closed as illustrated in Figure 2. With 5 the parts in this condition it is evident that accidental dislodgment of the plate *c* is positively prevented.

The manner of using the container for presenting to the bristles of the brush a predetermined quantity of powder separated from the bulk will now be described. Ordinarily it will be understood that all of the powder as indicated in Figure 2 will lie wholly below the slide *c*. The slide *c* will 10 normally be pushed in and held against movement by the clasp *b'* on the top *b*, at least so long as the latter is closed. The user raises the top slightly so as to withdraw the clasp *b'* from the flanged strip *c*³ and 15 then draws the slide *c* fully out. The top *b* will remain practically closed. When the container is inverted quickly the powder will, of course, fall on to the inner face of the top *b*. With the powder in this position 20 the slide *c* is pushed in and, acting as a cut-off, or what might be termed a slide-valve, will entrap a predetermined quantity of powder in the space between itself and the top *b*. When the container is restored 25 to its usual upright position the top *b* may be thrown back and the entrapped powder resting on the slide *c* will be exposed for the application of the moistened bristles of the brush thereto. Since the container is of generally 30 rectangular outline and its cross-sectional area is about equal to that of a tooth brush, there will be no wastage of powder 35

since all of the bristles will be applied to some part of the surface of the powder. Further, in the operation as described there 40 is no opportunity for any of the powder to leave the box, so no skill or care will be required in the manipulations and the only powder removed from the box will be that which actually adheres to the bristles. The 45 entire operation can be effected in a minimum of time. The container itself is simple and inexpensive and constitutes a package which overcomes the objections to existing containers and should materially increase 50 the use of tooth powder.

I claim as my invention:

An article of merchandise consisting of a portable container for tooth powder having a hinged top provided with a retaining clasp, the container being formed with a slot in its side wall adjacent to the open end and in the wall opposite to the hinged joint, the end walls of the container being crimped to form grooves in line with the slot, a partition plate extending through the slot and slidably mounted in said grooves, ears carried with the plate to limit its movements, and a flanged strip carried on the outer edge of the plate to close the slot when the plate is pushed in, the clasp of the cover overlying said flanged strip when the cover is closed and the plate is pushed in, said container being invertible to permit its contents to be divided by said partition plate, 65 substantially as described.

This specification signed this 1st day of November A. D. 1920.

LEO BIRNBAUM.
